ABSTRACT

A method of producing an effervescent, low carbon, boron steel in which a vacuum treatment is used to kill a steel melt containing sufficient oxygen to produce an effervescent steel by the addition of carbon.

9 Claims, No Drawings

METHOD OF PRODUCING A VACUUM TREATED EFFERVESCENT BORON STEEL

BACKGROUND OF THE INVENTION

This invention pertains to a method of producing an effervescent steel by a method which includes purifying molten iron by the use of sub-atmospheric pressure and the addition of boron in its reduced state.

Conventional melting practice for the production of very low carbon, low residual steels has used a basic open hearth furnace and aimed at the production of unusually high temperatures to obtain the high degree of oxidation necessary for the production of low carbon steel. It is also known to use oxygen to supplement the air used in open hearth combustion to provide this high degree of oxidation. Basic oxygen furnace (BOF) melting utilizing relatively high purity oxygen to provide heat by the oxidation of silicon, manganese and carbon contained in blast furnace iron may be substituted for open hearth melting.

Conventional low carbon, effervescent steels containing boron are known to resist aging. It is also known that these steels may be rolled into sheet to provide steel having good formability and good deep drawing characteristics. The usual constituents of these low carbon steels are about as shown below. It should be understood that all percentages referred to in this specification are based on weight.

Carbon	0.10% maximum
Manganese	0.05/0.50%
Phosphorus	0.001/0.035%
Sulphur	0.003/0.040%
Silicon	0.005/0.35%
Oxygen	0.001% minimum
Nitrogen	0.001/0.010%

It is also known that small amounts of residual alloys may be detrimental to the properties of these steels and typical maximum permissible amounts are as follows:

Tin	0.01%
Chromium	0.04%
Molybde- num	0.01%
Copper	0.10%

In addition, small amounts of deoxidizers such as aluminum, boron, vanadium, columbium and titanium have been added to these low carbon steels in varying combinations for a variety of additional purposes such as combining with carbon and nitrogen.

Steels of these compositions have been produced with a wide degree of deoxidation practice varying from rimming, semi-killed, killed and including combinations such as mechanical and chemical capping the steels in molds.

A more recent development in melting practice is to supplement the prior art furnace melting with a vacuum treatment so as to effect a further reduction in the carbon and oxygen in the steel by chemical reaction (1) so as to produce carbon monoxide.

An illustration of this combination is provided by U.S. Pat. No. 3,183,078 issued to T. Ohtake et al for "Vacuum Process for Producing a Steel for Non-Aging

"Enameling Iron Sheets." The killed steels disclosed in this patent contain aluminum and titanium.

A recent illustration of this combination is provided by U.S. Pat. No. 3,792,999 issued to K. Ruttiger for "Method of Producing a Drawing and Deep Drawing Steel Resistant to Aging, Particularly for Single-Coat Enameling." The steels of this patent contain boron.

In addition, U.S. Pat. No. 2,771,651 issued to E. R. Morgan et al. for "Method of Preparing Non-Aging Steels" discloses a method of adding a strong deoxidizer such as aluminum to chemically cap a rimming steel containing boron.

The low carbon, boron steels of the prior art have not been commercially successful because of the manner in which the steels respond to rolling, deep drawing and enameling. Some of the steels have been satisfactory but some heats have been either hot short during hot rolling, result in excessive amounts of scrap during deep drawing and/or are unsatisfactory because of 15 lected so as to provide a low residual alloy content. The mixture is melted under highly oxidizing conditions to provide from about 0.03 to 0.08 percent carbon. This preferred, but non-critical range of carbon of 0.03 to 0.08 percent will provide a sufficient degree of oxidation so that a vacuum treatment will result in reducing the carbon in the melt to about 0.005 percent. This reduction in carbon is due to the effect of the vacuum in enhancing the reaction of carbon and oxygen to produce carbon monoxide gas in accordance with chemical reaction (1):

The production of carbon monoxide will stop when the contained carbon is reduced to about 0.005 percent 15 and the melt will contain about 0.025 percent oxygen and be essentially killed.

The broad range of acceptable manganese content is from about 0.05 to 0.50 percent. For some applications the upper limit of manganese should be about 0.20 percent maximum to prevent an undesirable loss of hot strength. When the manganese falls below about 0.12 percent the steel may become hot short and cause difficulty in rolling. A preferred range of manganese would be from about 0.12 to 0.20 percent.

In a melt containing more than about 0.08 percent carbon it may be necessary to add sufficient oxygen to provide an oxygen: carbon ratio of about 1.4:1 to insure that the completion of the vacuum treatment will result in about 0.005 percent carbon and 0.025 percent oxygen. As is well known, oxygen may be added in either the elemental form as a gas or in the combined form such as an iron oxide, e.g. mill scale. Addition of oxygen in excess of the amount needed to provide 0.005 percent contained carbon after the vacuum treatment is undesirable because the excess oxygen may be detrimental to deep drawing.

Boron is an essential addition which is preferably added to the killed steel melt after completion of the vacuum treatment. The broad range of the boron addition is in an amount which will result in the recovery of 0.006 to 0.020 percent boron. This amount of boron is in excess of the amount necessary to chemically combine with normal nitrogen (0.003 to 0.005 percent) expected in these steels and which may cause strain aging. This excess boron is available to chemically combine with the carbon to form very small spheroidal iron-boro-carbides which are well dispersed throughout the steel and reduce porcelain enamel defects which are commonly associated with the large iron carbide particles which occur when boron is not present.

The killed steel containing no more than about 0.005% carbon and 0.025 percent oxygen is converted into an effervescing steel by the addition of carbon in an amount to recover 0.005 to 0.040 percent carbon. The added carbon reacts with the contained oxygen in the melt to evolve carbon monoxide and provide an effervescing steel which may be solidified in the usual manner.

The effervescing steels of this invention are usually solidified in cast iron molds and bottle top molds are preferred to provide a good yield from ingot to product without any significant losses due to cropping of sink-heads and unsound metal. It is also desirable to mechanically cap the ingots in bottle top molds.

A first specific example of the method of this invention is provided by the following description of melting

a 300 ton commercial heat of steel. A mixture of hot metal and low residual scrap was melted in a basic oxygen furnace. The melt containing 0.042 percent carbon and 0.07 percent oxygen was tapped into a ladle and 5 sufficient ferromanganese was added to provide 0.15 percent manganese. The melt was killed by subjecting to a vacuum for 28 minutes, which was followed by additions of boron and carbon. The effervescent melt was poured into bottle top molds which were hot rolled and cold rolled into sheet steel of the following composition:

Carbon	0.013%
Manganese	0.15%
Phosphorus	0.002%
Sulfur	0.013%
Copper	0.005%
Oxygen	0.020%
Nitrogen	0.005%
Boron	0.009%

The mechanical properties of the annealed cold rolled sheet steel were:

Yield strength	25,000 psi
Tensile strength	39,000 psi
Elongation	47%
Rockwell "B" Hardness	34

Another specific example of the method of this invention is provided by the following description of processing a 10 ton melt of steel in an electric arc furnace. The melt at tap contained 0.06 percent carbon and 0.047 percent oxygen and was subjected to a vacuum treatment for 10½ minutes at which time the evolution 30 of gas was complete and the melt was killed. The killed melt contained 0.005 percent carbon and 0.015 percent oxygen, and carbon was added to produce an effervescent steel containing 0.031 percent carbon and 0.011 percent oxygen. Boron was added to the melt 35 during pouring into open top cast iron molds and the solidified ingots were rolled into sheet steel of the following composition:

Carbon	0.031%
Manganese	0.17%
Phosphorus	0.008%
Sulfur	0.018%
Copper	0.06%
Oxygen	0.009%
Nitrogen	0.008%
Boron	0.012%
Molybdenum	Less than 0.02%
Tin	0.002%
Chromium	0.04%
Aluminum	Less than 0.005%

The mechanical properties of the annealed, cold rolled sheet steel were:

Yield strength	28,700 psi
Tensile strength	44,600 psi
Elongation	41%

We claim:

1. Method of producing a low carbon, boron sheet steel comprising:
  - a. providing a steel melt having low residual alloy content containing by weight no more than 0.01 percent tin, 0.04 percent chromium, 0.01 percent

- molybdenum and 0.10 percent copper, and 0.03 to 0.08 percent carbon,
- b. treating the steel melt with a vacuum to essentially complete the chemical reaction $C + O \rightarrow CO \uparrow$ by reducing the carbon to about 0.005 percent by weight to leave an excess of oxygen in an amount greater than will provide a O:C ratio of at least 1.4:1,
- c. adding boron to the vacuum treated melt in an amount sufficient to retain 0.006 to 0.020 percent by weight boron, 10
- d. adding sufficient carbon to react with the residual oxygen in the melt so as to provide an effervescing steel melt containing 0.005 to 0.04 percent by weight carbon, 15
- e. solidifying the effervescing steel melt, and
- f. hot and cold rolling the solidified steel to form sheet.
2. Method of producing a low carbon, boron steel sheet for deep drawing, said method comprising:
- a. providing a steel melt having low residual alloy content containing by weight no more than 0.01 percent tin, 0.04 percent chromium, 0.01 percent molybdenum and 0.10 percent copper, and 0.03 to 0.08 percent carbon, 20
- b. treating the steel melt with a vacuum to essentially complete the chemical reaction $C + O \rightarrow CO \uparrow$ by reducing the carbon to about 0.005 percent by weight to leave an excess of oxygen in an amount greater than will provide a O:C ratio of at least 1.4:1,
- c. adding boron to the vacuum treated melt in an amount sufficient to retain 0.006 to 0.020 percent by weight boron, 25
- d. adding sufficient carbon to react with the residual oxygen in the melt so as to provide an effervescing steel melt containing 0.005 to 0.04 percent by weight carbon,
- e. solidifying the effervescing steel melt in molds and rolling to form sheet, and
- f. hot and cold rolling the solidified steel to form sheet.
- 30
- 35

3. Method of producing a low carbon, boron steel sheet for deep drawing and porcelain enameling, said method comprising:

- a. providing a steel melt having low residual alloy content containing by weight no more than 0.01 percent tin, 0.04 percent chromium, 0.01 percent molybdenum and 0.10 percent copper, and 0.03 to 0.08 percent carbon,
- b. treating the steel melt with a vacuum to essentially complete the chemical reaction $C + O \rightarrow CO \uparrow$ by reducing the carbon to about 0.005 percent by weight to leave an excess of oxygen in an amount greater than will provide a O:C ratio of at least 1.4:1,
- c. adding boron to the vacuum treated melt in an amount sufficient to retain 0.006 to 0.020 percent by weight boron,
- d. adding sufficient carbon to react with the residual oxygen in the melt so as to provide an effervescing steel melt containing 0.005 to 0.04 percent by weight carbon,
- e. solidifying the effervescing steel melt in molds and rolling to form sheet, and
- f. hot and cold rolling the solidified steel to form sheet.
- 20
- 25
4. The method of claim 1 wherein step (a) includes adding oxygen in an amount to provide an O:C ratio of at least 1.4:1.
5. The method of claim 1 wherein manganese is added in an amount to provide up to 0.50 percent by weight manganese in the steel melt being treated with a vacuum.
6. The method of claim 1 wherein the melt is solidified in a mold.
7. The method of claim 2 wherein the melt is solidified in a bottle top mold.
8. The method of claim 7 wherein the melt being solidified in a bottle top mold is mechanically capped.
- 40
9. The method of claim 6 wherein the addition of boron of step (c) is made in the mold.
